UNITED STATES PATENT OFFICE.

ALBERT MERTON MONROE, OF TAFT, CALIFORNIA.

SLIP-SOCKET.

1,306,497.

Specification of Letters Patent. Patented June 10, 1919.

Application filed October 21, 1918. Serial No. 259,163.

To all whom it may concern:

Be it known that I, ALBERT MERTON MONROE, a citizen of the United States, and a resident of Taft, in the county of Kern and State of California, have invented certain new and useful Improvements in Slip-Sockets, of which the following is a specification.

My invention is an improvement in slip sockets, and has for its object to provide a device of the character specified especially adapted for use with fishing tools, for insuring a firm grip on the tool, and which is automatically engaged with the tool.

In the drawings:

15 Fig. 1 is a longitudinal section through the improved socket;

Fig. 2 is a section on the line 2—2 of Fig. 1, looking in the direction of the arrows adjacent to the line;

20 Fig. 3 is a side view of the socket detached.

The present embodiment of the invention is shown descending through a well casing 1 about to engage the tool 2 to be recovered.

25 The improved fishing tool, of which the slip socket is a part, comprises a sleeve or tubular casing 3, having at its lower end an inwardly extending annular shoulder 4, and the stem bore flares in both directions from

30 the shoulder, a second shoulder 5 being formed at the upper end of the upwardly flaring portion, the said shoulder 5 facing downwardly. It will be noticed that the flared portion above the shoulder 4 is of

35 considerable length. The upper end of the bore of the sleeve 3 is internally threaded and is engaged by a second sleeve 6, which has a reduced nipple 7 engaging within the threaded portion, and an annular shoulder 8 is formed at the inner end of the nipple, the said shoulder facing upwardly.

40 A connector 9 is threaded into the upper end of the sleeve 6 and this connector has at its upper end a threaded stem 10 which may be engaged with a socket in a suitable handling means, indicated at 11, for the tool. This connector 9 has openings 12 for the passage of water from above the tool downwardly through the bore of the tool.

50 The slip socket proper is a sleeve annu-

larly enlarged at one end, as indicated at 13, and having a tapering head 14 at the other which is shaped to fit loosely within that portion of the bore of the sleeve 3 between the shoulders 4 and 5, the said head having a shoulder 15 at its top, adapted to abut the shoulder 5 under circumstances to be presently set forth. This sleeve is split longitudinally from the collar 13 as shown, to form resilient fingers 16 connecting the sections of the head to the collar, and the splits at the head are of greatest width at the end of the head remote from the collar. Thus the sections of the head may be moved toward each other, that is, the head may be compressed. The inner surfaces of the head sections are toothed or corrugated as shown in Fig. 1, the teeth or corrugations facing upward.

55 A tubular casing 17 is mounted to slide in the nipple 7, the said casing having an annular shoulder 18 at its upper end for engaging the shoulder 8 to limit the downward movement of the casing, and a coil spring 19 is arranged between the casing and the connector 9, the spring acting normally to force the casing downwardly and to force the socket 13—14—16 downward.

70 In use, the device is lowered into the well casing as shown in Fig. 1. The upper broken end of the sucker rod will be guided into the bore of the head 14, by the flaring surfaces, it being seen that the lower end of the head is also tapering or flaring to correspond with the flare of the sleeve. The 75 tool will pass upwardly through the head, the head and socket moving upwardly to permit this movement. When the fishing tool is now drawn upward the tool 2 will be held, since the head 14 will be moved downward in the sleeve 3, and the sections of the head will be tightly compressed upon the tool. The greater the pull the more tightly will the head sections be compressed.

75 I claim:

80 A device of the character specified comprising a tubular casing or socket, a sleeve mounted to move in the socket, said sleeve being split longitudinally from near its inner end to the outer end to form a series of 85

tongues, having gripping jaws at their free ends, the casing or socket and the sleeve having at the end remote from the connection of the tongues coöperating inclined surfaces 5 to force the gripping jaws inward when the sleeve is moved downward, a sleeve above the first named sleeve and a spring above

the last named sleeve and normally pressing said sleeve downwardly, the said sleeve having means for limiting its downward movement to a point where the first named sleeve is in normal position. 10

ALBERT MERTON MONROE.
